1 Claim. (Cl. 33—104)

Our invention relates to a drafting implement, combined with a protractor.

The object of our invention is to obtain an isosceles, right angled triangle which is adapted to be used as a set square, protractor or ruler and in which one triangle is enough to measure any desired angles and to draw various lines in any desired directions.

Various forms of implements of this type have been proposed but no type in general use at the present time can be used to measure over 90° or 180°, whereas the triangle combined with a protractor according to our invention may be used to measure any desired angles, from 0° to 360°. 15 According to our invention a right angled isosceles triangle consisting of celluloid, bakelite or other transparent material is formed with a quadrantal opening whose curved edge is radially graduated to form a protractor and on the opposite side of this opening auxiliary dividing lines are drawn radially from the center of the protractor.

Our invention will be better understood from the following description when considered in connection with accompanying drawing and its scope 25 will be pointed out in the claim.

In the drawing:

Figure 1 is a plan view of one embodiment of our invention.

Figure 2 is a plan view of another embodiment of our invention, and

Figures 3, 4 and 5 illustrate examples of the use of the implement.

Referring to the numerals on the drawing, 1 is an isosceles triangle made of celluloid, bakelite or other transparent material in which is formed a quadrantal opening 2, as in Figure 1. Both side edges 3 of the opening 2 are parallel to the equal sides of the triangle 1 and a scale 4 is marked on the curved edge of the opening 2, said scale being divided radially from a corner point O of the side edges 3 and on the equal sides of the triangle 1 auxiliary dividing lines 5 are drawn radially from the focal point O so that angles

from 0° to 270° around the focal point O may be indicated by these auxiliary lines 5. In this triangle the inclined edge 6 may be graduated to be adapted for use as a ruler or straight edge.

In the modification shown in Figure 2, the triangle is provided with a plurality of curved slots 7, the curvature of said slots gradually decreasing from the point O to the hypotenuse of the triangle, each curved edge of these slots being marked with a scale ranging from 0° to 90°. 10

The implement according to our invention is constructed as above described and can be used to measure any desired angle from 0° to 360°; for example, 156° from a line OY may be measured in such a manner that the line OY registers 15 with the definite auxiliary line O' and a line OX at the graduation 66 on the scale 4 is drawn, thus the desired angle XOY is obtained.

To measure 30° at the point O' from a line AB as shown in Figure 3, the line AB registers on 20 the third line 5 intersecting a line OC' drawn by the side edge of the triangle 1; thus the desired angle BO'C is obtained.

In drawing plural lines at different angles, for example 3°, 6°, 7°, 12°, and 22°, said lines 25 are drawn radially from the focal point O of the opening 2. An angle of 3° is formed by placing the device so that line AB passes through point O and the 3° graduation of scale 4 and utilizing edge 3 to draw line OC. Other angles 30 are correspondingly formed.

We claim:

A drafting instrument consisting of an isosceles triangle of transparent material provided with a segmental opening having straight edges 35 which are radial to a definite focal point and having a curved arcuate edge with graduations thereon representing degrees of a circle, the sides of the triangle being provided with protracting lines registering with the lines on the curved 40 edge of the segmental opening and concentrating at the same focal point.
